UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEGRAPH SWITCHING SYSTEM.

Application filed February 1, 1922. Serial No. 533,362.

To all whom it may concern:

Be it known that I, CLARENCE E. LOMAX, a citizen of the United States of America, and a resident of Chicago, Cook County, and 5 State of Illinois, have invented certain new and useful Improvements in Telegraph Switching Systems, of which the following is a specification.

The present invention relates in general 10 to telegraph switching systems, and more specially to systems of this character comprising a plurality of telegraph stations each having a line extending to a central exchange or switching point, together with 15 suitable automatic switching devices at the exchange for connecting any calling telegraph line with any desired called telegraph line. A system of this kind is useful in banks or other business establishments as a 20 means of communicating between the different departments, and in case telegraph apparatus of the printing type is used, as is contemplated, the system is especially useful in that it preserves a record of all communications.

While ordinarily there would be no particular difficulty in providing means for switching one line of a plurality of lines in connection with any of the other lines, in 30 the case of telegraph lines, the problem is complicated by the fact that such lines are normally operated on closed circuit, and special arrangements have to be provided for establishing the interstation circuits at the 35 same time that the local circuits of the stations involved are broken, in order to avoid opening the circuit at any station during the switching process.

The particular arrangement provided for 40 this purpose by the present invention will now be described and its operation will be explained in reference to the accompanying drawings, which shows diagrammatically the apparatus and circuits involved in setting up a connection between the telegraph station A and the telegraph station B.

Although as previously indicated it is intended to use the invention in connection 45 with printing telegraph equipment, such apparatus is exceedingly complicated, and since the invention has to do merely with the establishment of the interstation circuits, it has not been considered necessary to show complete station equipment of this compli-

cated type. The telegraph equipment which 55 is shown at station A, therefore, comprises an ordinary sounder magnet M and an operator's sending device comprising the switch S and key K. In addition to the telegraph apparatus, there is provided an 60 automatic impulse transmitter or calling device CD, which may be of the type shown and described in the patent to Keith, No. 1,279,352, issued Sept. 18, 1918, which is used for controlling the automatic switch 65 associated with this station at the exchange. The key K² is provided for closing the circuit of the calling device. The lamp L is a busy lamp, and is lighted whenever it is attempted to establish connection with a 70 busy station.

The line conductors 2, 3, 4 and 5 extend to the central exchange or switching point and terminate in the individual connector switch H, which is preferably of the mechanical 75 construction shown and described in the patent to Keith, Erickson & Erickson, No. 815,176, granted March 13, 1906. As will be understood this switch may have access to one hundred lines which terminate in contact sets arranged in a plurality of horizontal rows or levels. In order to connect with a desired line, the switch is first operated to raise its wipers vertically to a position opposite the particular row or level in which the 85 desired line appears, and is then operated to rotate its wipers into connection with the desired line. In the case of the connector H, these operations of the connector are all controlled by the subscriber at station A by 90 means of the calling device CD, as will appear more clearly hereinafter.

There may be one hundred stations in the system illustrated, and each station is provided with a connector switch exactly like 95 the connector H. Each connector has access to all of the lines in the system, and thus the party at any station, by suitably operating his individual connector switch, can establish a connection with any other station. 100

It may be that under some circumstances a number of the stations will be located in the same department, and of such a character that it is a matter of indifference to a 105 calling subscriber as to which of the particular stations in such department he obtains connection with. Certain arrange-

ments shown herein are arranged to take care of this situation by providing for automatic trunk selection by the connector switches in the case of station lines which may be arranged in groups under the circumstances mentioned. A subscriber, in calling a department having a number of grouped stations, will call the number of the department, and will automatically establish connection with a line leading to the first idle station in such department.

Having pointed out the general features of the invention, its operation will now be described more in detail, and for this purpose it will be assumed that the party at station A desires to establish a connection with the party at station B. Before proceeding, it will be well to point out that the telegraph apparatus at the station A is included in a closed circuit which extends from ground at G' by way of resistance r' , resting contact of armature 60 and the said armature, conductor 4, switch S, magnet M, conductor 2, normally closed contact springs controlled by armature 76, and resistance r^2 to the grounded battery B'. It will be seen also, that the telegraph apparatus at station B is included in a closed circuit similar to the one described for station A, except that it includes the battery B². In practice, the batteries B' and B² will be the same or different batteries depending on the distance between the stations and perhaps on other circumstances. The telegraph battery, or batteries, are preferably of high voltage, as is most suitable for telegraph systems. The other battery symbols shown in the drawing all refer to the same battery, which is the one used for supplying current to the automatic switches at the exchange.

Now, since the two stations are normally connected in a local closed circuit, the establishment of a connection between the two stations will necessarily involve the opening of both local circuits and the completion of an interstation circuit in which the telegraph equipment at both stations is connected in series. While the inter-station circuit might conceivably include both batteries, in case different batteries were employed at the two stations, according to the present arrangement only one battery is used in each connection, and the battery used is the one at the called station.

To extend a connection, the key K² is first operated in order to connect up the calling device CD after which the calling device is operated in accordance with the two digits in the number assigned to the called station, which may be assumed to be the number 55. When the key K² is operated, a circuit is completed over conductor 5 for the line relay 16 of the individual switch H, and the said relay energizes and completes a circuit at armature 61 for the slow-

acting release relay 17. Upon energizing, the latter relay disconnects relay 15 at armature 62 and at the same point connects ground to the conductor 6, whereby a test potential is placed on the test contacts 10 and 11 and multiples thereof in banks of the other connector switches. In addition to the foregoing, relay 17 prepares a circuit for the vertical magnet 24 at armature 63. The calling device is now operated in accordance with the first digit. Five interruptions are accordingly produced in the circuit of the line relay 16, which deenergizes five times and transmits a like number of impulses to the vertical magnet 24 over the following path: From ground by way of armature 61 and its resting contact, resting contact of armature 75 and the said armature, armature 63 and its working contact, shaft controlled off-normal springs 27 and 29, winding of the slow-acting series relay 18, and the winding of the vertical magnet 24 to battery. In response to impulses received over the above circuit the vertical magnet 24 operates to raise the switch shaft step by step until the wipers 35, 36 and 37 stand opposite the fifth horizontal level of bank contacts. Relay 18 is energized in series with the vertical magnet and being slow-acting, remains in operated position during the vertical stepping movement. At its armature 64, relay 18 maintains the impulsive circuit closed through its own winding and the vertical magnet, notwithstanding the shifting of the shaft controlled off-normal springs, which takes place at the first vertical step of the switch. At the end of the vertical movement, relay 18 falls back and transfers the impulsive circuit from the vertical magnet to the rotary magnet 25.

When the calling device is operated in accordance with the second digit of the number, five more interruptions are produced in the line circuit and the line relay 16 is deenergized five times as before. This time, however, the line relay transmits impulses to the rotary magnet 25 over the following path: From ground by way of armature 61 and its resting contact, resting contact of armature 75 and the said armature, armature 63 and its working contact, off-normal springs 27 and 28 armature 64 and its resting contact, resting contact of armature 67 and the said armature, winding of the slow-acting series relay 20, and the winding of the rotary magnet 25 to battery. By the operation of the rotary magnet, the wipers 25, 36 and 37 are rotated step by step and are finally brought to rest in engagement with the particular set of bank contacts in which the line of station B is terminated, designated in the drawing by reference characters 38, 39 and 40. Relay 20 is energized in series with the rotary magnet and

being slow-acting, remains in operated position during the rotation of the switch. At armature 70, relay 20 closes a circuit for the slow-acting relay 22, which is thus also maintained energized during the rotary movement of the switch. At armature 77, relay 22 disconnects the test wiper 36 from the winding of the switching relay 21 and connects it by way of armature 73 and its resting contact to the winding of the test relay 19. It is noted, that since the test relay is connected up at the beginning of the rotary movement, means is provided on the series relay 20, consisting of armature 71, to provide against the opening of the rotary magnet circuit by the test relay in case the test wiper 36 should engage a grounded test contact while rotating.

If we assume now that the line of station B is busy when called, when the test wiper 36 comes to rest in engagement with test contact 39, it will find a ground potential and the test relay 19 will be energized. The rotary movement having been completed, relays 20 and 22 now fall back, and a locking circuit is completed for the energized test relay as follows: From the grounded conductor 6 by way of armature 66 and its working contact, normally closed contact springs controlled by armature 77 of relay 22, armature 73 and its resting contact, and the winding of test relay 19 to battery. In its energized position the test relay opens the rotary magnet circuit at armature 67, breaks the circuit to the lower winding of the switching relay 21 at armature 66, and at armature 68 connects conductor 3 to the exchange battery, thus lighting the lamp L at station A. Since this indicates to the calling party that the desired station is busy, he will release the connection by restoring key K².

It may be assumed, however, that station B is idle when called. Under these circumstances, when the test wiper 36 comes into engagement with test contact 39, it will find no ground potentials and the test relay 19 will not be energized. Accordingly, when relays 20 and 22 fall back at the end of the rotary movement, a circuit will be established for the switching relay 21 as follows: From the grounded conductor 6 by way of armature 66 and its resting contact, lower winding of relay 21, resting contact of armature 77 and the said armature, test wiper 36, test contact 39, conductor 6', armature 62' and the winding of relay 15' to battery. Relays 21 and 15' are energized in series over the above circuit, and the latter relay disconnects conductor 4' from ground at armature 60'. The switching relay 21, on energizing, establishes a locking circuit itself at armature 72, opens the circuit of the test relay 19 at armature 73, opens the operating circuit at armature 75, and at ar-

mature 74 connects direct ground to the test wiper 36. In addition to the foregoing, at armature 76 relay 21 disconnects the line conductor 2 of station A from the battery B and connects it instead to wiper 37, this operation taking place simultaneously with the operation of armature 60' by relay 15' which was previously described. Both of the local telegraph circuits have now been broken and an inter-station circuit has been established which may be traced as follows: From ground at G' by way of resistance r', resting contact of armature 60 and the said armature, conductor 4; switch S, magnet M, conductor 2, working contact of armature 76 and the said armature, wiper 37, contact 40, conductor 4', switch S', magnet M', conductor 2', normally closed contacts controlled by armature 76' of relay 21', and the resistance r³ to the grounded battery B². The establishment of the above circuit completes the operations incident to securing the desired connection.

The two stations being now in communication with each other, the party at station A may open the switch S, and by suitably manipulating key K can transmit code signals to the party at station B, which are there rendered audible by means of the sounder magnet M'; or, in case printing telegraph apparatus is used at the two stations, the party at station A will spell out the message he desires to transmit on the keyboard at his station, whereupon the message will be printed out on tapes at both stations simultaneously. It will be understood, of course, that when the automatic printing equipment is used, the transmission of a message does not require the presence of the receiving operator at the other end, the message which is sent being printed on tape as stated, where it is accessible to the operator or other party at the receiving station when he returns.

The release of the connection is accomplished by restoring key K², as previously mentioned. The restoration of this key breaks the circuit of line relay 16, which falls back and permanently opens the circuit of slow-acting release relay 17. The latter relay upon deenergizing, takes ground off from conductor 6 in order to clear the line of station A for incoming calls, and also, at armature 63, closes a circuit for the release magnet 26. Upon energizing, the magnet 26 withdraws the holding pawls which permit the switch shaft to restore to normal position, the release magnet circuit being broken at off-normal spring 30, just before the switch is completely restored. The removal of ground from conductor 6, also causes the switching relay 21 to be restored, and ground is removed from test wiper 36, thus permitting the deenergization of relay 15' in the switch associated with

the called station B. All the apparatus is now in normal condition, ready for other calls.

The automatic trunk selecting feature of connector H will now be briefly explained. The connectors are preferably provided with extra banks of test contacts, such as the test contacts 10 and 38, associated respectively with stations A and B. The extra test contacts which are associated with all single or individual stations, are left dead or disconnected, as shown in the case of the test contact 38 which is associated with the line of station B. In the case of grouped stations however, which are selected automatically responsive to the calling of the group number, which it may be stated, is the number of the first station in the group, each extra test contact is connected to its associated regular test contact. This is true of the test contacts associated with all the stations in the group except the ones associated with the last station in the group, which are left separate or disconnected from each other. The manner in which the test contacts of a grouped line are connected, is shown in the case of contacts 10 and 11 associated with the line of station A.

Assuming now, that the connector H is operated to establish connection with a set of contacts in which is terminated a line extending to the first station of a group. If this station is busy, the test contact engaged by test wiper 36 will find a ground potential and the test relay 19 will be energized, as previously explained. At the end of the rotary movement relay 20 will fall back and open the circuit of relay 22, but the latter relay being slow-acting will not deenergize immediately. When relay 20 falls back a circuit is completed for the stepping relay 23 as follows: From the grounded test contact engaged by test wiper 35, (this test contact is permanently connected to the test contact engaged by test wiper 36), by way of test wiper 35, resting contact of armature 69 and the said armature, working contact of armature 65 and the said armature, interrupter contact of rotary magnet 25, and the winding of stepping relay 23 to battery. Relay 23 is energized over the above circuit, and locks itself at armature 79, at the same time closing a circuit for the rotary magnet 25 at armature 80. Relay 20 being now deenergized, the slow-acting relay 22 is energized in parallel with the rotary magnet, and is thus prevented from deenergizing. The operation of the rotary magnet advances the switch wipers into engagement with the next set of bank contacts. The rotary magnet also breaks the circuit of the stepping relay 23, which accordingly falls back and breaks the rotary magnet circuit, which then deenergizes also and again closes its interrupter contact.

If the next set of contacts is engaged also, the foregoing operations will be repeated, and it will be understood accordingly, that the rotary movement will continue either until a set of contacts is reached which is associated with an idle station, in which case the test wipers will no longer find grounded contacts, or until the wipers arrive at the last contact set in the group, in which case the test wiper 35 will find no ground potential regardless of whether the station associated with this last contact set is busy or idle. If idle, neither test wiper will find a ground and communication with the selected called station will be established by the energization of switching relay 21, as previously pointed out, but if busy, the test contact 36 will find ground potential, and the test relay 19 will be locked up to light the busy lamp at the calling station.

It will be seen from the foregoing, that suitable switching apparatus is provided, whereby closed circuit telegraph stations, such as stations A and B for example, may be connected in a series circuit without interrupting the flow of current through the instruments at the two stations during the process of establishing the connection. This is, of course, accomplished by the energization, in the case of the stations mentioned, of the switching relay 21 of the connector H at the same time or slightly before the energization of relay 15' in the connector associated with the called station. In order to insure the correct timing of these relays, relay 15' is provided with a slug of copper, as indicated in the drawing, which renders it slightly slow to pull up. Resistances such as r' to r^4 , inclusive, are provided to prevent short-circuiting of the batteries or the telegraph instruments during the establishment and release of inter-station circuits. The arrangement shown and described is intended for use in connection with that type of equipment in which it is positively required that the flow of current must be maintained through the telegraph instruments at all times, except during the actual transmission of code signals. Certain types of telegraph equipment, however, have less rigid requirements and permit the momentary breaking of the instrument circuits, preliminary to the transmission of reception of a message; or, the system may be of the type in which a momentary opening of the circuit is required to be introduced in order to prepare the equipment for the transmission or reception of messages. In such cases the resistances r' to r^4 , inclusive, may be omitted, and ordinary make and break spring combinations may be used at the connectors in place of the make before break spring combinations which are shown at armature 76 of the connector H and at armature 76' of the connector associated with station B.

Having described the invention what is considered to be new will be pointed out in the appended claims.

What I claim is:

5. 1. In a telegraph switching system, a plurality of closed local circuit telegraph stations, there being three or more of said stations, automatic switches for connecting any two stations in series, and relay means in 10 said switches for establishing a series circuit between any two connected stations before opening the local circuits of said stations.
15. 2. In a telegraph switching system, a plurality of closed local circuit telegraph stations, there being three or more of said stations, automatic switches for connecting any two stations in series, said switches being individual to said stations and controlled 20 therefrom, and relay means in said switches for completing the series circuit between any two connected stations before the local circuits are broken.
25. 3. In a telegraph switching system, calling and called stations, closed local circuit telegraph instruments at each station, an automatic step by step switch directly controlled from the calling station to establish a circuit including the instruments at both 30 stations in series, and relay means in said switch for breaking the normally closed local circuits after the series circuit is completed.
35. 4. In a telegraph switching system, calling and called stations, closed local circuit telegraph instruments at each station, a battery included in the closed local circuit at each station, and an automatic selectively movable switch directly controlled from the 40 calling station to establish a series circuit including the instruments at both stations and only one of said batteries.
45. 5. In a telegraph switching system, calling and called stations, closed circuit telegraph instruments at each station, a battery included in the closed local circuit at each station, an automatic selectively movable switch directly controlled from the calling station to establish a series circuit including 50 the instruments at both stations and the battery at the called station, and means for switching the battery at the calling station out of circuit.
55. 6. In a telegraph switching system, a plurality of telegraph stations, telegraphic sending and receiving equipment at each station, automatic selectively movable switching mechanism controlled from any calling station to connect the sending equipment 60 therewith the receiving equipment at any called station to establish communication between said stations said switching mechanism being nonresponsive to said telegraph sending equipment, and an operator controlled variable impulse sender at each sta-
- tion for controlling said switching mechanism as set forth.
7. In a telegraph switching system, calling and called stations, closed circuit telegraph instruments at each station, separate 70 battery and ground connections in each local circuit, an automatic selectively movable switch controlled from the calling station to establish a series circuit including the instruments at both stations, the ground connection at one station, and the battery connection at the other station, and means for automatically opening the other ground and battery connections when the series circuit is established.
8. In a telegraph switching system, calling and called stations, closed local circuit telegraph instruments at each station, a battery included in the closed local circuit at 80 each station, an automatic selectively movable switch directly controlled from the calling station to establish a connection between said stations, and relay means in said switch effective upon said connection being established for completing a series circuit 85 including the instruments at both stations and only one of said batteries.
9. In a telegraph switching system, a plurality of stations, telegraph instruments at each of said stations normally in a closed local circuit involving separate ground and battery connections, an automatic switch individual to each of said stations and directly controlled therefrom for extending 90 a connection to a called station, and relay means in said switches for automatically completing a series circuit including the instruments at both stations and only one battery.
10. In a telegraph switching system, calling and called stations, closed local circuit battery and a ground connection included in the closed local circuit at each station, an automatic selectively movable switch directly controlled from the calling station to establish a series circuit including the instruments at both stations and the battery at the called station, and means for switching the battery of the calling station and the ground at the called station out of circuit.
11. In a telegraph switching system, calling and called stations, closed local circuit telegraph instruments at each station, a battery and a ground connection included in the closed local circuit at each station, an automatic selectively movable switch controlled from a calling station to establish a series circuit including the instruments at both stations and the battery at the called station, and automatic means in said switch effective 120 after said series circuit has been completed, for switching the battery at the calling station and the ground at the called station out of circuit.
12. In a telegraph switching system, call-

ing and called stations, closed local circuit telegraph instruments at each station, a battery included in the closed local circuit at each station, an automatic selectively movable switch directly controlled from the calling station, to establish a series circuit including the instruments at both stations and only one of said batteries, and relay means in said switch for establishing said series circuit without, at any time, disturbing the current flow over said instruments.

In witness whereof, I hereunto subscribe my name this 23rd day of December, A. D., 1921.

CLARENCE E. LOMAX.
